UNITED STATES PATENT OFFICE.

JOHN PERRY, OF KENSINGTON, LONDON, AND SIDNEY GEORGE BROWN, OF NORTH ACTON, ENGLAND.

GYRO-COMPASS.

1,291,695.

Specification of Letters Patent.

Patented Jan. 14, 1919.

Application filed August 7, 1917. Serial No. 184,955.

To all whom it may concern:

Be it known that we, JOHN PERRY and SIDNEY GEORGE BROWN, both subjects of the King of Great Britain, residing, respectively, at 25 Stanley Crescent, Kensington, in the county of London, England, and Edward Road, Willesden Lane, North Acton, in the county of Middlesex, England, have invented certain new and useful Improvements in or Relating to Gyro-Compasses, of which the following is a specification.

This invention relates to the construction of gyro-compasses especially for use on ships, and has for its chief object to provide the necessary gravitational control of the gyroscope, which gives the north seeking property, without subjecting the gyroscope to appreciable disturbing forces due to rolling, pitching or other short period motions of the ship. The compass may be of the general type described in the specification of our United States application No. 60,770 in which the friction around the vertical axis of a gyro frame mounted in a pendulous support is substantially eliminated by means of a reciprocating movement; the present invention however is not confined to any special type of compass.

According to this invention the pendulous or gravitational factor which controls the gyroscope acts through a relay or intermediate source of power. The pendulous factor may therefore be made very small compared to the mass of the gyroscope, and the gyro-casing, including the gyro wheel and any parts moving with the casing, may be mounted substantially in neutral equilibrium so that rolling or other periodic or irregular movements of the ship exert no direct torque upon the gyro-casing.

The rotation of the gyro wheel in its casing causes rotatory movement of the air in the casing and an outwardly directed pressure of air due to centrifugal force; we may utilize this air as the intermediate source of power by directing, for example, the air from a nozzle into two channels leading to a weight displacing device by which weight may be shifted from one side to the other of a transverse lever preferably at about the level of the gyro axis. The weight displacing device preferred is in the form of a pair of communicating bottles or vessels at oppo-

site sides of the axis of the gyro-casing and containing oil or other liquid, the gravitational factor or pendulum controlling the air jet so as to vary the pressure in the channels and cause flow of oil from one bottle to the other according to the direction in which the righting torque is to be applied. It will be seen that as the controlling weight is at the end of a substantially horizontal lever arm it is in the most efficient position for exercising its controlling force, in contrast to the direct control of a pendulum which for small displacements is at its position of minimum efficiency. A characteristic of great importance is due to the fact that the weight displacement is out of phase with the movement of the gravity control or pendulum, since the maximum differential air pressure and consequently maximum movement of the liquid occur at the end of the pendulum swing when the pendulum is moving at its minimum speed, while the air pressure and liquid movement are about zero when the pendulum is moving at maximum speed through its central position. By this difference in phase in conjunction with the mounting in neutral equilibrium the quadrantal error is eliminated, as has been found experimentally.

To exercise a strong damping effect on any oscillations of the gyro-casing which may be set up, we may employ a second set of air controlled oil bottles or vessels working in opposition to the main bottles but with a more contracted passage so as to cause slower flow of oil and consequently a large time lag. The difference in phase produces the desired damping action.

In order that the said invention may be more clearly understood and readily carried into effect, we will describe the same more fully with reference to the accompanying drawings, in which:—

Figure 1 is an elevation of the gyro-compass embodying our invention, with the gimbal rings in section.

Fig. 2 is a view at right angles to Fig. 1, partly in section on the line $x-x$ Fig. 1.

Fig. 3 is a sectional plan on the line $y-y$, Fig. 1.

Figs. 4, 5 and 6 are detail views, to a somewhat larger scale, of the oil bottle pendulum device.

Figs. 7 and 8 show a modification of the

pendulum device, in which an auxiliary gyroscope is employed.

Figs. 9 and 10 illustrate a modification of the compass control.

5 Fig. 11 shows a further modification; and

Figs. 12 and 13 show simplified constructions in which a separate controlling pendulum is dispensed with and the pendulous mounting of the gyroscope employed for 10 the control of the independent source of power.

Referring to the construction illustrated in Figs. 1 to 6, A is the gyro-casing within which the wheel rotates around a normally 15 horizontal axis. B is the orienting frame or ring carrying the card b, within which frame the casing A is free to turn around the horizontal axis a at right angles to the gyro axis. C is an outer pendulous frame 20 carrying the frame B which can turn around the vertical axis b' and is reciprocated along that axis so as to reduce the friction to a minimum in accordance with our specification No. 60770 already referred to. The 25 bearing and means for producing reciprocation are inclosed in the box c at the bottom of the frame C, which is mounted in the usual gimbal rings D. E is an air nozzle on the casing A, through which a small jet 30 of air escapes at a pressure depending upon the action of the rotating gyro-wheel. The nozzle projects through an opening in the frame B. F is a pendulum arm carrying a small shutter or air director f which partly 35 covers the nozzle E and directs the air to one side or the other according to the angular position of the pendulum. G, G are two small communicating oil bottles mounted on the casing A receiving the pendulum floats 40 f' which rest on the oil in the bottles G so that the pendulum F is controlled by the differential oil level. H, H are the main oil bottles which exercise the righting torque 45 around the axis a of the casing A. J, J are the second pair of bottles acting around the axis a to produce damping of the oscillations. K is a small air chamber or box provided by the blade or partition k (see the detail plan, Fig. 6) into two compartments 50 into which the air from the nozzle E is directed in a variable manner. Each compartment is connected by the small pipe k' to an air pipe k² connecting the upper end of one bottle H to the bottle J at the opposite side 55 of the axis a, the bottles being cross connected in pairs as shown in Fig. 3. The bottom connections for the oil are through the pipes h and j respectively for the pair of bottles H and J, so that oil can flow in one 60 direction between the two bottles H according to the relative air pressures on the two surfaces and in the opposite direction between the two bottles J, the passage in the latter case being considerably more restricted to give a substantial lag in attaining 65

equilibrium. The rate of flow may be adjusted by the small screw adjustment j' below one of the bottles J.

The gyro casing A together with all the parts which are carried by it is substantially 70 in neutral equilibrium around the axis a so that rolling or other periodic or irregular movements of the ship exert no direct torque upon the gyro-casing. The orienting frame B should also be arranged so that the mounting of the gyro is kinetically symmetrical around its three axes and to enable this condition to be attained adjustable weights L are mounted on arms l extending from the lower side of the frame B in the vertical 80 plane through the gyro axis, the weights being set so that the total amounts of inertia, including that of the casing A, are balanced and there is no tendency for the gyro mounting to set itself in any special relationship 85 to the plane of roll or pitch of the ship.

Owing to the neutral equilibrium of the casing A gravitation exerts no direct control over its position but any tilt relatively to the vertical (which continuously changes its 90 position in space as the earth rotates) acts upon the pendulum F through the oil in the pendulum bottles G, the oil flowing from one bottle to the other according to the direction of tilt of the casing A. As shown more especially in the detail views Figs. 4 and 5 the bottles G are carried on a base g mounted adjustably on a bracket g' which is fitted to the casing A, the adjustment of the bottles and attached parts for balancing being effected by the screw g² acting against the spring g³. The oil passage g⁴ between the bottles is restricted by the adjustable needle valve g⁵ so that the rate of flow can be regulated to any required degree. The pendulum arm F is mounted on the knife edge bearing f² on posts g⁶ on the base g and the floats f' are at the ends of the curved cross arm f³ which passes through the covers of the bottles G. Any change in relative level 100 of the oil in the bottles G due to tilting of the casing A causes the arm F to turn relatively to the casing and consequently moves the air director or shutter f across the nozzle E (see the detail views Figs. 5 and 6) with 110 the result that the air is deflected unequally into the two compartments of the box K causing unequal pressure in the opposite pipes k'. The director f may be a simple centrally placed bar as shown or may be in 120 the form of a small plate with air hole which directs the air into the chamber K.

The pipes k' and cross pipes k² are so connected to the main bottles H that the differential air pressure causes a flow of oil 125 between the bottles such as to exert, owing to the displacement of weight from one side of the axis a to the other, a torque tending to right the casing and bring it into central position. As long as the tilt exists the oil 130

bottles H are out of balance and the torque continues, the strength of the torque depending upon the differential pressure of air, that is upon the amount of tilt, and upon the period of the tilt, time being necessary to cause any substantial displacement of oil. When normal position of the gyro-casing is reached the oil in the bottles G has almost returned to its normal position of equilibrium so that the air pressure in the bottles H is now almost equalized. To damp out oscillations the second pair of bottles J is provided, usually of smaller capacity than the bottles H and having, as already described, a more restricted oil channel between them. Since these bottles J act against the bottles H the righting torque is reduced by an amount depending on the oil displacement in the bottles J but such displacement has a considerable time lag and for short period disturbances the righting torque is not substantially reduced, while the difference in phase between the action of the two pairs of bottles rapidly damps out any oscillations of the casing A which may have been set up and consequently damps the associated oscillations of the compass around the vertical axis b'.
 As already pointed out the controlling weight acts at the end of a substantially horizontal lever arm so that a small addition of weight to one side or the other exerts an appreciable righting torque which torque is variable and out of phase with the pendulum.

While short period movements such as rolling and pitching of the ship have no direct disturbing effect on the gyro-system owing to the fact that it is mounted in neutral equilibrium such movements cause acceleration pressures on the oil in the various bottles which would, if uncompensated, cause some disturbances in the balance. As however the relation between the torque applying and the pendulum bottles is under control by the adjustment of the oil passage between the bottles G, the small effects of short period movements on the pendulum may be made to cause such differential air pressures in the bottles H and J as will compensate for the acceleration pressure on the oil in these bottles so that no appreciable disturbance of the compass reading is caused by such short period movements.

The pendulum device above described is one specially designed to give a normal condition of neutral equilibrium which remains substantially unaffected by short period movements of the compass while responsive to the slow changes in the vertical due to rotation of the earth, but other long period pendulum arrangements may be employed; for example, a small auxiliary gyroscope may be attached to a pendulum or equivalent gravity control device, such gyroscope

lengthening the natural period, as is well known, or the pendulum may be connected to a damping device which prevents appreciable short period movements but allows the pendulum to respond to long period forces.

The modification shown in Figs. 7 and 8 employs a pendulum controlled by an auxiliary gyroscope.

In this construction a pendulum F' is mounted on knife edge bearings on the end of a bracket arm n belonging to a bracket N which, as in the case of the bracket g' carrying the bottles G, extends from one face of the gyro-casing past the edge of the frame or ring B.

A downwardly extending bracket arm n' carries a small dash pot M containing a viscous liquid into which the lower end of the pendulum F' extends. The upper end of the pendulum is made in the form of a ring f' inclosing a small auxiliary gyro-wheel O mounted in a frame o which is carried on vertical pivot points o' in the ring f'. The axis of the gyro-wheel O is level and parallel with the axis of the main gyro and the rotation is in the same direction.

Any force exerted on the pendulum F' tending to cause angular displacement is resisted by the gyro-wheel O which is free to precess around its vertical axis. A small centralizing spring o² connected to the frame o acts to return the gyro-wheel to its normal central position parallel to the plane of the main gyro-wheel or gyro-casing A.

The pendulum F' is stabilized by the small auxiliary gyroscope and is almost unaffected by short period disturbances, but responds to the slow change in the vertical due to the rotation of the earth. The air control may be of the type already described, the pendulum carrying the small air director f controlling the air from the nozzle E belonging to the gyro-casing.

The modification shown in Figs. 9 and 10 illustrates a damped pendulum which may take the place of either of the pendulum devices already described and also a different method of applying the righting torque to the gyro casing. Only one side of the casing is shown but it is to be understood that the arrangement of pendulum and air nozzle is duplicated at the other side.

In this modification the air pressure in the casing is used directly for the production of a righting torque by the differential action of two air nozzles E', one on each side of the casing and oppositely directed, so as to discharge the air and cause a reactive pressure against the external air acting around the horizontal axis a of the casing A. In this modification a dash pot M' containing a very viscous fluid, such as beeswax, is mounted on an arm m turning about an axis m' and supported in brackets m² mounted on

the casing A, the dashpot receiving at one side a fixed blade m^3 secured on the casing and at the other the lower blade end of a pendulum F^2 mounted on an axle f^5 that carries the two arms f^6 and the air director f^7 which lies in front of the nozzle E', made as shown in Fig. 8, in the form of a long narrow slit.

It will be seen that any tilt of the casing 10 causes a retarded relative movement of the pendulum F^2 through the dashpot M, which displaces the air director f^7 over the nozzle, increasing or reducing the effective air aperture according to the direction of movement. 15 At the other side of the casing A the similar device causes an opposite displacement so that there is a differential air discharge through the two nozzles E' and consequently a reaction against the external air which 20 generates a righting torque around the axis a of the casing A. The air director f^7 preferably half covers the nozzle E' in normal position. A small weak restoring spring f^8 tends to return the pendulum F^2 to normal 25 position relatively to the casing A.

Various other methods of utilizing a relay action in the control of the gyroscope can be employed. For example, the air blast from the nozzle instead of being utilized to produce pressure may act through an electric circuit, the nozzle being placed between two heated wires which it cools differentially so as to control an electric current to a motor adapted to exert a righting torque on the 30 casing A. This is indicated diagrammatically in Fig. 11, where the pendulum F^3 , damped as in the arrangement already described, carries on its arm f^9 a pair of platinum wires f^{10} normally symmetrically placed with relation to the nozzle E², these wires being included in a heating and motor circuit comprising the motor P mounted on the axis of the gyro-casing A, a permanent magnet p providing the field for the motor. 35 The motor current varies in direction and strength according to the relative cooling of the wires f^{10} , no current flowing to the motor when the wires f^{10} are of equal temperature while any displacement due to tilting of the 40 casing and consequent movement relative to the pendulum F^3 moves one or other of the wires into the air blast and causes differential cooling of the wires and a righting torque around the axis of the casing A which depends on the strength of the current through the motor.

In the modification shown in Fig. 12 the air blast device is controlled by the pendulous mounting of the gyroscope itself in the frame C (Figs. 1 and 2) the vertical axis of the orienting frame or ring B coinciding with the axis b' of the frame C. The air nozzle E and air box K are carried by the gyro-casing A as in the constructions illustrated in Figs. 1 to 8, the nozzle projecting

through an aperture in the frame B while a small arm F^4 is fixed to the frame B below the knife edge a' of the casing A and projects in front of the nozzle E. Any tilting of the casing A relatively to the frame B causes differential action of the air blast on the air box K as already described although the frame B and support C may swing through a considerable angle and cause the arm F^4 to pass to and fro in front of the nozzle. The use of a separate pendulous device is thus avoided.

Instead of an air deflecting arm such as F^4 a small conical movable jet F^5 secured on the frame B may be provided, as shown in Fig. 13, the jet being placed just in front of the air nozzle E and leading the air through a reduced aperture which moves relatively to the air box K according to the relative movements of the casing A and frame B.

What we claim and desire to secure by Letters Patent of the United States is:—

1. In a gyro compass, a gyroscope, mounted so that its axis may be oriented in the "N—S" direction, a gravity controlled device and an independent source of power controlled by the said gravity device and adapted to act upon the gyroscope to maintain its axis of rotation in the "N—S" direction.

2. In a gyro compass, a gyroscope including a gyro-casing mounted in substantially neutral equilibrium around its horizontal axis, so that the axis of rotation of the gyroscope may be oriented in the N—S direction, a gravity controlled device and an independent source of power controlled by the said gravity device and adapted to act upon the gyroscope around its horizontal axis of suspension so as to maintain its axis of rotation in the "N—S" direction.

3. In a gyro compass, a gyroscope including a gyro-casing mounted to turn about a horizontal axis, a weight displacing device by which mass may be moved across the axis of the gyro-casing, a gravity controlled device and an independent source of power controlled by the gravity device to effect the operation of the weight displacing device.

4. A gyro-compass as claimed in claim 1, comprising a gyro casing filled with air and having a directive air outlet under the control of the gravity device.

5. A gyro-compass as claimed in claim 4, provided with a differential air director for the said air outlet, by which air director the gravity device exercises its control.

6. In a gyro-compass, a gyroscope including a gyro-casing mounted to turn about a horizontal axis, a pair of interconnected liquid vessels mounted on the casing at opposite sides of its said axis, a gravity device and a source of power controlled by the said gravity device to displace liquid from

one vessel to the other, for the purpose specified.

7. In a gyro-compass as claimed in claim 6, a gyro-casing filled with air and provided with an air outlet, an air director under gravity control and air channels into which the air is differentially directed and through which pressure is applied to the liquid in the aforesaid vessels, for the purpose specified.

10 8. In a gyro-compass as claimed in claim 6, a second pair of interconnected liquid vessels having a more restricted communicating passage and means for displacing liquid in the opposite direction to the displacement in the main vessels but at a slower rate, for the purpose specified.

15 9. In a gyro-compass, a gyroscope comprising a gyro-casing mounted to turn around a horizontal axis and a frame carrying the gyro-casing, a small pendulum device comprising a pair of communicating

vessels partly filled with liquid and mounted at each side of the casing axis and a pivoted lever carrying a pair of floats supported by the liquid in the said vessels, and a source 25 of power controlled by the said pendulum device and adapted to exert torque around the axis of the said gyro-casing, for the purpose specified.

10. In a gyro-compass, a gyro-casing 30 filled with air and provided with an air outlet, a pair of interconnected liquid vessels mounted on the casing on opposite sides of its axis, a pair of air channels connected to the said vessels, a gravity controlled device 35 and an air director deflecting the air differentially into the said channels under the control of the said gravity device, for the purpose specified.
